[57] CLAIM

The ornamental design for spout, as shown and described.

DESCRIPTION

FIG. 1 is a perspective view of our new design of a spout;
FIG. 2 is a front elevational view of our new design of the
spout;

FIG. 3 is a rear elevational view of our new design of the
spout;

FIG. 4 is a left side elevational view of our new design of
the spout, a right side elevational view thereof being a mirror
image of the left side elevational thereof;

FIG. 5 is a top plan view of our new design of the spout; and,
FIG. 6 is a bottom plan view of our new design of the spout.
